THREAD WINDING MACHINE

Hans Treckmann, Wuppertal-Oberbarmen, Germany, assignor to Messrs. Halstenbach & Co., Wuppertal-Wichlinghausen, Germany

Application March 14, 1938, Serial No. 202,048
In Germany February 26, 1937

31 Claims. (Cl. 242—35.5)

This invention relates to automatic winding machines, and has for its object to provide a machine of this description which, in a continuous operation, conducts bobbins, which have been placed in a magazine, to the spindles of the winding machine, holds them in position, carries out the winding automatically and after the winding operation automatically ejects the bobbins, and cuts off short the ejected bobbins and passes them in orderly disposal to a suitable conveying means, whilst empty bobbins are continuously being fed automatically from the magazine and secured in position for continuation of the winding process, without it being necessary in the course of this continuous operation to perform any actuations by hand. In addition to the ordered and fully automatic winding of the bobbins it is ensured by the machine according to the invention that even the finest yarns, such as artificial silk, can be wound on this machine.

The invention is illustrated by way of example in the accompanying drawings, in which—

Fig. 1 is an elevational side view of the machine according to the invention.

Fig. 2 is a front view of the winding machine, from which, for the sake of better illustration, the carriage conveying the empty bobbins from the magazine to the spindles has been omitted.

Fig. 3 shows the bobbin carriage in its stationary position before it engages in the magazine.

Fig. 4 is an elevational view illustrating the engagement of the carriage in the magazine containing the empty bobbins.

Fig. 5 is an elevational view illustrating the bobbin carriage on its way to the spindles and, in dash-dotted lines, the position of the carriage when the empty bobbins are applied to the spindles.

Fig. 6 is a view of the pawl mechanism associated with the closing means for the intercepting container which receives the wound bobbins after they have been let fall from the spindles.

Fig. 7 is a modification showing in elevation of a modified form of an intercepting container.

Fig. 8 shows a further embodiment of an intercepting container in the form of a pivotally mounted trough.

Fig. 9 shows an intercepting container in the form of a pivotally mounted trough, in which the ejected bobbins are deposited on a studded board.

Fig. 10 shows in section from the front the

provision of a pivotally mounted trough on a four-spindle machine.

Fig. 11 is a plan view of the device for advancing the studded boards below the ejection aperture.

Fig. 12 is an elevational view corresponding to Fig. 11.

Fig. 13 is a section taken on the line XIII—XIII in Fig. 11.

Fig. 14 is a section through the studded board conveying means taken on the line XIV—XIV in Fig. 11.

Fig. 15 shows on enlarged scale a partial view of the bobbin presser head and the thread guide gear.

Fig. 16 is a section on the line XVI—XVI in Fig. 15.

Fig. 17 shows the thread guide in the position of release.

Fig. 18 is a plan view showing the feeding of the thread to the shears.

Fig. 19 is a side elevation of the clutch mechanism, later to be referred to, in enlarged detail.

Fig. 20 is a top plan of a portion of the mechanism shown in Fig. 19, and

Fig. 21 is a view in perspective of a portion of the operating parts of the machine, to which special attention will later be directed.

1 represents the bed of the machine on which is mounted a frame 2. In this frame is a gear box 3 (Fig. 2) which contains any suitable conventional type of mechanism (not shown) for driving, from off a main shaft 21, one or more spindles 4, and for reciprocating and rotating one or more thread guide rods 5. The bobbin spindles 4 and the thread guide rods 5 are conducted out of the gear box at the front.

From the upright frame 2 there extends a horizontal frame 6, which projects forwardly

of the machine and carries in axially shiftable fashion in a suitable bearing 8, corresponding to the number of spindles 4 projecting from the gear box, the bobbin pressers 7 borne by shafts 9. Each shaft 9 is conducted out of the bearing

8 in opposite direction to the supporting point for the bobbin 10, and is furnished at a distance from the bearing 8 with a thread 11, on to which there is screwed a milled nut 12. In the space between the nut 12 and the bearing 8 there

engages a stud 13 on a pivoted fork 14, which is mounted on a shaft 15. This shaft 15 is rotatably mounted in suitable bearings 16 secured to the frame 6. The studs 13 form the ends of a rod 17 passing through the ends of the fork

14 and project out of the fork 14 on either side

for engagement behind the nut 12. The width of the fork 14 and the length of the control rod 17 guided by the fork are such that the studs 13 are capable of engaging in two bobbin pressers 7. If the fork 14 with its studs 13 is rocked outwards, the shaft 9 of the presser 7 will also be moved in the outward direction and the head 18 of the bobbin presser will be moved out of engagement with the bobbin 10. The return of the presser 7 into the position in which it is pressed against a bobbin 10 takes place by means of a spring 19 (Fig. 15), which is disposed within the bearing 8 about the shaft 9 of the presser and bears on the one hand against a shoulder 9' on the rod 9 and on the other hand against the end face 20 of the bearing 8.

Each of the spindles 4 has a head 22 which is provided with a mandrel for engagement in the bobbin 10. The spindle 4 is not axially shiftable. The thread guide rod 5, which projects out of the gear box 3 between each two spindles, and somewhat above the center line of the spindles, is furnished on the part projecting out of the gear box with a thread 23 extending almost up to the long side bearing 24, in which the thread guide rod 5 is mounted to be axially shiftable and rotatable and which is mounted on the frame 6. Each thread guide rod 5 receives from suitable mechanism within the gear box both a rotary and a reciprocative motion.

On each thread guide rod 5 there is slidably arranged a thread guide support 25, which encompasses the thread guide rod 5 by means of a sliding bush 26. This bush 26 is open at the one end and at this point engages with a die 27 furnished with a similar thread, which die, by means of an angularly disposed arm 28, is mounted by the shaft 29 on the body of the thread guide support and is held in position by two guide members 30. The die 27 surrounds by means of an elongated aperture 31 a guide rod 32, which ensures the upright position of the body of the thread guide support 25. On the body of the thread guide support there are provided to the right and the left two projectory thread eyelets 33, 33 (Fig. 16), which extend over the positioned bobbins 10 and allow the thread to run on to the bobbin during the winding operation.

The thread guide support 25 which is held in engagement with the threaded portion 23 of the thread guide rod 5 by the threaded die 27 is longitudinally shifted, by the rotary motion of the rod 5, against the action of a spring 34 which bears at one end against the body of the thread guide support 25 and at its opposite end, within the bearing 24, against an abutment 5^a on the thread guide rod 5.

Upon the advance of the thread guide support 25 out of an initial position in the vicinity of the gear box 3 it, in the position indicated in the dash-dotted lines of Fig. 15, has moved into engagement with the stop 35 on the end of a rod 39. This rod is shiftable in abutments 36, 37 on the bearing 24 and carries, in the part thereof projecting beyond the abutment 37, a tup 38 which is adjustable on the rod 39 beyond the abutment 37 and can be maintained in any adjusted position thereon by a winged nut 40. The tup 38 engages with a guide stud 38^a in a fork 41, the main portion of the tup bearing against the fork. This fork is pivotally mounted upon a stud 42^a located at the bottom of the bearing 24 in the abutments 42 thereon. With the thread guide support 25 engaging the stop 35

as shown in the dash-dotted line of Fig. 15, the tup 38 on the rod 39 will have moved the fork 41 into the dash-dotted position shown in this figure. When now the thread guide support 25 is moved away from the stop 35 thereupon the fork 41 will be returned to its initial position, as shown in the full lines of Fig. 15, by a spring 41^a one end of which is secured to the fork and the other to the abutment 36.

10 The guide rod 32 for the thread guide support 25 is borne at its opposite ends by angle levers 44 which are secured to the rod by set screws 45 (Figs. 1, 15). These angle levers at the fore end of each guide rod 32 are pivotally mounted on arms 46 which extend from the fixed bearings 24. At the opposite or rear end of each guide rod the angle levers are pivoted directly to the fore end of the gear box 3. All the guide rods 32 for all the thread guide supports 25 are 15 equipped with these angle levers 44, and for turning all the angle levers 44 for all the rods 32 there is provided a linkage 47 through which force may be directed for rocking the angle levers in reverse directions. When the rocking motion 20 is in a clockwise direction, as viewed in Fig. 2, the guide rods 32 will be moved upwardly whereby threaded engagement between the threaded die 27 of each thread guide support 25 and the thread guide rods 5 will be broken, whereupon 25 the spring 34, which, due to the progressive movement of the thread guide support 25 during the winding has become compressed, is free to return the thread guide support 25 back to its initial position of winding, the return movement continuing until the thread guide support 30 strikes a stop 48 adjustably mounted on the rod 32. If now the moving force on the linkage 47 be such as to move the angle levers in a reverse or anti-clockwise direction, as shown in Fig. 2, 35 thereupon the rods 32 will be moved down to again complete threaded engagement between the dies 27 of the thread guide supports 25 and the thread guide rods 5 for continuing the winding operation.

40 During the winding operation the fork 41 is in a position shown in the full lines of Fig. 15 and forms a latch for holding latched in place a stud 43 on a control lever arm 49. This control lever as will presently be explained, is a 45 spring activated lever, and when the stud 43 is released by shift in the position of the fork 41, then the arm 49 will be released to turn, after which the arm may be returned to its original latched position. The lever arm 49, and in fact 50 the whole control lever, of which this arm forms a component part, has a rocking movement as the arm is released from and returned to its latched engagement with the fork 41. The lever arm 49 is fixed to a rotary shaft 53 at one end of this shaft. Fixed, also, to the shaft 53 is an arm 47^a to the end of which the linkage 47 is 55 pivotally secured. When the lever 49 is in its latched position with the fork 41, it will then have moved down the guide rods 32 and thereby 60 will hold the thread guide supports 25 with associated dies 27 in threaded engagement with the thread guide rods 23. On the release of the lever from its latched engagement with the fork 41 its consequent turning, following its release, 65 will through these same parts raise the guide rods 32 and thereby move the thread guide supports into disengagement with the thread guide rods 5.

70 Fixed to the end of the rod 53, opposite that end to which the lever arm 49 is fixed, is a lever 75

arm 49' in direct opposing relation to the lever arm 49, the two arms combining to form the complete control lever. At its end the arm 49' is connected through a folding joint 50 to a two-armed lever 51 which lies in extension of the control lever to which it is attached, and is pivotally supported on the bed of the machine by mounting on a bearing 52. When the arm 49 of the control lever is released from its latched engagement with the fork 41 this arm will move upwardly and the arm 49' of the complete control lever will move downwardly. The inner arm of the lever 51 will consequently move downwardly, and its outer arm, beyond the point of its pivotal attachment, will move upwardly. On the return of the control lever to its initial latched position, or, in other words the latching of its arm 49 to the fork 41, a reverse movement of the levers takes place. These rocking movements of the levers are availed of to effect various operations, and reference will first be made to that for the control of a stop mechanism (not shown) which stops or starts the mechanism which drives the spindles 4 and actuates the thread guide rods 5.

Arranged in a position adjacent to and above the inner arm of the lever 51 is a rock shaft 62, the reverse turning of which controls the stop mechanism above referred to. Fixed to this shaft 62 is an arm 63 to which is pivoted a link 63' which has pivotal connection with the inner arm of the lever 51 by a pin 51' on the arm of the lever entering a slot 63'' in the link 63'. Fixed, also, to the rock shaft 62 is an arm 62' which is under the action of a tension spring 64 interposed between the arm and a case 55 for mechanism later to be referred to. The normal action of the spring working through the arm 62' is to turn the rock shaft 62 in a clockwise direction, as viewed in Fig. 2 when the rod will actuate the stop mechanism to stop the drives for the spindles and thread guides. A reverse turning of the arm 62', with tensioned extension of the spring 64, will turn the rock shaft 62 in a reverse or anti-clockwise direction, as viewed in Fig. 2, whereupon the stop mechanism will be actuated to start or throw the drives for the spindles and thread guides into operation. In the latched position of the control lever, which is the position shown in Fig. 2, where the lever 49 is in latched engagement with the fork 41, the arm 49' of the control lever will have been turned up as will the inner arm of the lever 51. In consequence through the link 63' and arm 63 the rock shaft 62 will have been turned in an anti-clockwise direction in an amount sufficient, acting through the stop mechanism, to throw the drives for the spindles and thread guides into action. At such time the spring 64 will be extended and thereby tensioned. When now the control lever is released from its latched engagement, or, in other words, when its arm 49 is released from latched engagement with the fork 41, thereupon the lever arm 49' and the inner arm of the lever 51 will turn downwardly thereby allowing the spring 64 through the arm 62' to move the rock shaft 62 in a clockwise direction and actuate the stop mechanism to stop the drives for the spindles and thread guides.

The control lever, which includes the lever arms 49 and 49', and the lever 51 are under the tensional control of a spring 54. One end of this spring is secured to the end of the outer arm of the lever 51. The opposite end of the spring is secured to the case 55. When the control lever

is in latched engagement with the fork 41, the end of the lever 51, to which the spring 54 is attached, will have been moved down thereby tensioning the spring 54. Upon detaching or unlatching the control lever from the fork 41 the spring 54, exerting force to draw upwardly the end of the lever 51, will, through the line of levers, displace the arm 49 of the control lever upwardly away from its latched connection with the fork 41, and incidentally will rock the shaft 53 to which the control lever is secured in a clockwise direction. Thus it will be seen that the line of levers when latched are under the tensional control of the spring 54 which causes their displacement as explained when unlatched from the fork 41. If now the end of the lever 51 be depressed a reverse action of the levers will take place, the control lever will again become latched, and the shaft 53 to which the control lever is fixed will be turned in an anti-clockwise direction.

Located above the end of the lever 51 within the case 55 is a clutch mechanism which is activated by the lever 51 when the arm 49 of the control lever is released from its latched engagement with the fork 41, and which clutch mechanism is thrown out or disengaged when the arm 49 of the control lever is returned to its latched engagement with the fork 41. The clutch mechanism includes a continuously rotating worm wheel 58 which is driven by a worm 59 on a shaft 60 turned in any suitable manner in the operation of the machine. The worm wheel 58 is journalled to turn on the casing 55 and carries on its under side one or more pins 57. Beneath the wheel 58 is located a freely rotatable cam disk 56 which bears a pin 56'. This pin is adapted to have clutch engagement with one of the pins 57 on the continuously rotating wheel 58 when the cam disk is lifted, whereupon during the continuance of such engagement the cam disk 56 will be rotated by the wheel 58. The cam disk is lifted by the outer lever arm of the lever 51 as this arm turns upwardly on the release of the arm 49 of the control lever from its latched engagement with the fork 41. The outer arm of the lever 51 has secured to it a finger 56'' which extends laterally beneath the cam disk 56 and acts to lift the disk as the lever arm becomes lifted. The cam disk is held against rotation by a stop 61 on the body of the frame of the machine which enters a slot 61' in the edge of the disk. When the stop is in this slot the cam disk cannot be turned. The cam disk can be turned when the lever arm has lifted it above the plane of the stop 61 at which time the disk will be thrown into clutch engagement with the rotating wheel 58 and be turned thereby. The action is one in which the cam disk 56 is made to have only a single complete revolution after the throwing in of the clutch, disengagement or throwing out of the clutch being effected at the completion of such revolution. To this end the cam disk is formed on the under side thereof with a projection or cam 56^a, which, when the cam disk is approaching the end of its single revolution will enter between the disk and the finger 56'' on the forward arm of the lever 51 and depress this arm, thereby turning the lever 51 and returning the arm 49 of the control lever again into latched engagement with the fork 41. The complete revolution of the cam disk 56 will now have brought the slot 61' in the edge of the disk into alignment with the stop 61 on the frame, whereupon the cam disk 56 will be thrown out

of clutch engagement with the wheel 58 by means of an arm 69. This arm is pivoted to the casing 55 and the end of the arm has drawing engagement with the top of the cam disk 56 by means of a spring 70, one end of which is connected to the end of the lever 69, and the other to the fore end of the lever 51.

The cam disk 56 when rotated by the wheel 58, on being thrown into clutch engagement therewith, brings about certain operative effects. The disk is provided on the top with a cam 71 which is fixed to the disk. Against this cam, as shown in Fig. 1, there bears by means of the wheel 72 a lever 73 which rocks the forks 14 on the shaft 15 by way of connections 74, 75 and 76 (Fig. 1), thus causing the bobbin pressers 7 to be withdrawn in the bearings 8 so that the wound bobbins 10 will fall away from the spindles. Owing to the form of the cam 71 the bobbin pressers remain in the withdrawn position until the empty bobbins taken from the magazine, as will later be explained, have been brought forward by the carriage 68, and it is not until the carriage has moved the empty bobbins into position to be clamped between the bobbin pressers 7 and the heads of the spindles that the cam 71 releases the forks 14 so that, under the action of the springs 19 built into the bearings 20, the heads 18 of the bobbin pressers are able to move against the new bobbins and press them against the mandreled heads 22 of the spindles.

The cam disk 56 has, also, on its under side a crank pin 65 which engages in a slot in a pivotally mounted lever 66 even in the lifted or clutch forming position of the disk. This lever 66 is mounted on a journal 66^a on the bed 1. A longitudinal slot in the lever 66 is engaged by a stud 67 located on the under side of the carriage 68. Through these connections the carriage 68 will be moved with a long sweep to the left, as viewed in Fig. 2, from an initial position beneath the magazines 144, presently to be referred to, containing empty bobbins, to a position beneath the spindles and thence will be moved back to its initial position.

During its movement the carriage performs various operations, the essential one of which is to receive empty bobbins from the magazines 144, carry them, and place them on the spindles in position for winding in replacement of the wound bobbins which have dropped out. The magazines 144 correspond in number to the number of spindles 4. As indicated in Fig. 2, the magazines 144 are at the right of the spindles. The magazines have two guides 145, 146 (Fig. 1) having the empty bobbins 143 disposed between them. At the lower end of the guides 145, 146 there is located a laterally shifttable closure slide 147, which extends in the form of a throughgoing plate below all the magazines 144. Laterally of each magazine there is provided in the said plate an ejection opening 148, which is covered by an angular gripper plate 149, the angular opening being directed towards the appertaining magazine. The length of the gripper plate 149 is such that it can be moved between the guides 145, 146 into the stacked empty bobbins. The opening in the gripper is so dimensioned that it corresponds to the largest diameter or, in the case of shaped bobbins, to the distance between two bobbins. The empty bobbins 143 are held in position in the magazines 144 by the slide 147 effecting closure in the position of rest. The member 147 is moved by means of a stud 150 on the carriage 68 moving below the closure mem-

ber. After displacement the member 147 returns under the action of a spring 151 into its normal position, which is that shown in Fig. 3. The spring 151 is attached to a post 152 secured to the machine frame. The slide 147 is guided in corresponding guides on the frame of the machine.

The carriage 68 adapted to move below the closure slide 147 comprises a main frame 153 on the lower side of which there is located the stud 67 previously referred to, which engages the rocking lever 66. On the upper side of this frame 153 there are four bearings 154 fitted with a spaced set of cross rods 154' which engage in oblique slots 155 in the sides of a shiftable frame 156. This frame 156 rests normally by its own weight on the cross rods 154' with the ends of the rods normally contained at the top ends of the slots. The frame 156 possesses recesses 157 corresponding to the spacing between the magazines 144, and the spindles 4, which recesses are such that in each case there may rest therein the ends of the empty bobbins dropped from out of the magazine. On this frame 156 of the carriage is located a stud 150 which is brought into engagement with the gripper plate 149 in the operation of the machine. After the completion of one winding operation and preliminary to the delivery of a new set of empty bobbins to the winding spindles the carriage is moved to the right as shown in Fig. 2 by the lever 66, whereupon the stud 150 on the carriage will be brought into engagement with the gripper plate 149 borne by the slide 147 whereupon the gripper plates will grip into the stacked empty bobbins and at the same time the slide 147 will be moved by the width of an empty bobbin towards the right, whereupon the openings 148 in the slide below the stacked bobbins will allow the bottom bobbins to fall out of the magazine, while by reason of the grippers 149 the bobbins situated above are retained. The bottom lay of empty bobbins thus released to fall out drop as shown in Fig. 4 into the recesses 157 in the frame 156 of the carriage. The carriage now having received its complement of empty bobbins performs a long rocking movement to the left carrying the empty bobbins. An intermediate position is shown in Fig. 5 in which the carriage has already moved somewhat away from the magazines 144. Upon this initiated movement of the carriage the stud 150 has released the closure slide 147 which, under the action of the spring 151 returns to its normal position of closure. Thus the closure slide 147 will close the bottoms of the magazines and the gripper plates will be withdrawn from the magazines. The empty bobbins 143 in the magazines will then follow up and be held in the magazines by the plate 147 then occupying a closed position. The carriage, rocked by the lever 66, continues its movement to the left until it reaches an extreme left position as shown in the dash-dotted lines in Fig. 5 where the carriage is shown immediately below the spindles, and the unwound bobbins borne by the carriage in vertical alignment with the spindles. Shortly before reaching this extreme position, the frame 156 movably mounted on the carriage frame as it is, will come into contact with a fixed stop 166 on the bed of the machine whereupon the frame 156, upon the further advance of the frame 153 of the carriage cannot be shifted further to the left on account of the stop, consequently, under the action of the oblique slot guides 155 in the sides

of the carriage frame 153, the frame 156 is lifted vertically and the empty bobbins carried by it are lifted to the levels of the spindles 4, and held in this position until the action of the cam drive 71 through connections 72, 73, 74, 75 and 76 has released the bobbin pressers 7 to hold the unwound bobbins thus positioned in readiness for winding when the spindle drive next starts.

During the movement of the carriage 68 to the left, before it registers the limit of its movement and the bobbins carried by it are lifted into placement for winding, further operations take place through elements activated and controlled by the moving carriage. These further operations include the positioning of the trailing thread, its holding, and cutting. In this connection it will be explained that during the progress of the carriage 68 to the left the wound bobbins, already released from the spindles by the withdrawal of the presser 7 through action of the cam 71, have fallen to lie within the compartments 79 of an intercepting container 77. The wound bobbins have but a short fall into this intercepting container which lies immediately below the plane of movement of the carriage 68. The container 77 comprises single channel-like compartments corresponding in their location to the disposal of the spindles (Fig. 2), the partitions between the single compartments preferably consisting of sheet metal ribs 78 bent into V-shaped form so that the wound bobbins falling down from the spindles are each able to enter in reliable fashion a corresponding compartment 79 of the container. It is the thread left trailing from the wound bobbins lying within the compartment 79 that is positioned, held, and cut at points lying below the spindles, and below the points where the threads are being held in order that the trailing threads may not only be cut, but the portions of the trailing threads lying above the cuts will continue to be so held so that they will extend over the spindle heads where they may be clamped between the head ends of the empty bobbins applied to the spindles, in order that the threads thus trapped may wind upon the bobbins when the wind is continued.

The carriage 68 during its reciprocatory movement is guided in part at the front by its bottom plate resting in the guide 159^b (Fig. 18). This guide extends along the path traversed by the carriage. On the opposite side the carriage is guided by a long blade 158 laterally projecting from the bottom of the carriage, and which engages in a grooved slideway 159^a. This slideway 159^a extends along the under side of the magazines and terminates at a point between the magazines and the space beneath the spindles. It does not extend under the spindles. Accordingly, when the carriage has moved to a point beneath the spindles the main portion of the blade 158 will lie forward of the slideway 159^a, and present an edge 158' over which the trailing thread may extend. The forward end of the blade 158 is provided with a bevel 168. Accordingly, when the carriage 68 moves forward to the left, to bring the fresh supply of empty bobbins carried by it under the spindles, the beveled end 168 of the blade will strike the trailing threads connecting as they do with the wound bobbins already deposited to lie in the compartments 79, and as the movement of the blade continues will move the threads aside so that they will trail over

the edge 158' of the blade 158. The trailing threads thus initially positioned are further positioned and held by means of shiftable grippers or clamps 167 which not only position, but, also, hold the threads tightly clamped at points lying immediately below the heads of the spindles so that the threads thus held may be clamped between the heads of the freshly inserted bobbins and the mandreled heads of the spindles when the bobbin pressers 7 are released to hold the freshly inserted bobbins. Associated with the clamping means for the thread are shears 85. These shears are disposed below the thread holding clamps in order that they may cut the thread at points lying below the clamps so that after the cutting the threads may continue to be held by the clamps as aforesaid. Both the shiftable grippers 167 and the shears 85 are actuated by the moving carriage 68. To this end there is mounted in suitable manner upon the frame of the machine a horizontally extending fixed plate 169. This plate lies above the plane of the blade 158 and in position where the front edge 169' of the plate will lie just inwardly removed from a vertical plane in which lies the edge 158' of the blade 158. Mounted upon the top of this plate are the shiftable grippers 167. These grippers 167 consist of a pair of opposing gripper portions which extend beyond the edge 169' of the plate 169, and of which one pair of gripper portions is assigned to the gripping and holding of each thread, there accordingly being four pairs of gripper portions in all. One each of the pairs of gripper portions assigned to each thread is fixed to a bar 176, the second of each pair of gripper portions is fixed to a bar 180. The bar 176 is held by claws 177 to be longitudinally shiftable along the surface of the plate 169 and to project beyond the end of the plate 169 at the end directed towards the magazines where the bar is squared for the purpose of forming a suitable abutment face. The opposite or fore end of the bar 176 has an angularly turned end 176'. Interposed between this end and a post on the plate 169 is a spring 183. In pivotal engagement with the outer end of this turned end 176' is a rocking lever 178 pivoted at the point 178' to the fore end of the plate 169. The free end of the rocking lever is pivotally connected to the bar 180 which extends along the top face of the plate 169 between it and the bar 176. In consequence if the upper gripper bar 176 be moved by force applied to its end abutting face the lower gripper bar 180 by way of the rocking lever 178 will be moved along the plate 169 in an opposite direction. In this way the two portions of each pair of grippers 167 are moved together and meet in the position where they engage and hold the thread, already initially positioned by the advancing blade 158, vertically below a spindle axis.

It is the moving carriage 68 which applies this moving force to the end abutting face of the bar 176. When the carriage has become so far advanced that the blade 158 carried by it has moved the trailing threads 128 into position to be gripped and held by the grippers 167 thereupon a lever 158^a on the carriage will be brought into engagement with the end of the bar 176 for moving it. For the purpose of obtaining a more general movement and to permit of a certain resiliency and compensate for further advance movement of the carriage

after the grippers have been brought into engagement with the threads this lever is pivotally mounted in a one directional fashion at 181 on the carriage and at the other end is held in a state of tension by a spring 182. After the advance movement of the carriage has caused the grippers to engage and hold the threads the retraction of the carriage will allow the grippers to resume their normal position, this being effected by means of the spring 183 which causes the rods carrying the gripping parts to resume their normal positions of rest.

The shears 85, previously referred to, which cut the threads when held by the grippers, are disposed on the under side of the plate 169, there being shears for each thread to be cut. One blade of each of the shears is rigidly secured to the plate 169 in an oblique position. The second blade of each of the shears is pivoted at the point 170 to its companion fixed blade on the plate 169. At their opposite free ends these movable blades of the shears each has in it a slot in which lies a pin 171 borne by a rod 172. This rod is longitudinally shiftable within ways 173 on the under side of the plate 169, and the end of the rod 172 extends beyond the end of the plate 169 in a direction towards the magazines. The rod 172 is held in a normally retracted position for holding the blades of the shears open by means of a spring 174, one end of which is secured to an offset 175 from one of the ways 173, and the other end of the spring is affixed to an arm 173^a on the rod 172. Upon the advance of the carriage 68 and abutment 158^b on the end thereof, which is secured to the carriage and can be adjusted to a certain length by suitable provision of set screws, strikes against the end of the rod 172 and thereby closes the pivotal blades of the shears enabling them to then cut the threads. In this connection it is to be observed that the relative position of the abutment 158^b, which activates the shears, in relation of the abutment 158^a, which activates the thread grippers, is such that the grippers will be actuated to grip the thread before the action of the shears takes place, the two operations following in relative sequence as the carriage 68 advances. The advancing movement of the carriage accordingly occurs in such manner that the blade 158 will move the trailing threads from the fallen bobbins to the edge of the plate 169 which carries the thread grippers and shears. When thus initially positioned the threads are engaged by the grippers which close under the action of the lever 158^a. The grippers accordingly hold the thread until, upon the further advance of the carriage 68, the shears will close under the action of the abutment 158^b. After the cutting of the threads the grippers will still continue to hold these portions of the threads then positioned to extend over the spindle heads all the time while the carriage is supplying empty bobbins 143 to replenish the spindles, and will continue to hold the threads until through release of the presser bars 7 the positioned bobbins have been clamped in place between the spindle heads and presser bars 7, thus clamping the threads between the heads of the spindles and the heads of the bobbins whereupon the threads will wind upon the bobbins when the wind is continued. In fact the grippers are not opened, and the same may be said of the shears, until the carriage 68 moves back in the direction of the magazines under the action of the rocking lever 66 when the shears are first allowed to open under the action of 75

the spring 174, the abutment 158^b then being released, and then on the release of the lever 158^a the spring 183 will restore the grippers to their normal open positions of rest.

As previously explained the wound bobbins are released from the spindles to lie in the compartment 79 of the container 77, and the dwell of the wound bobbins in these compartments continues during the holding and cutting of the trailing threads and until the retraction of the carriage 68, when the wound bobbins are released from the compartments, as will presently be explained. Each of the compartments 79 is formed at its forward end with an inclined face 84 against which the end of the wound bobbin strikes when falling down from the spindle so that the bobbin during its fall into the intercepting container or compartment is tilted somewhat in relation to the spindle and thrown forward in the compartment into which it falls. This arrangement is made so that the thread wound upon the bobbin in a few layers at the lower or head end thereof at the termination of the winding operation owing to the return movement of the thread guide 25 as previously explained, will so lie that it will be struck by the blade 158 on the moving carriage and so positioned that it may be held by the grippers 167, and cut by the shears 85. At the same time, owing to the small space between the wound bobbin held in the intercepting container 77 and the shears 85, there will be but a small end of thread on the bobbin subsequently expelled from the container which is advantageous inasmuch as long loose ends of thread always give rise to entanglements and cause the loosening of further layers of thread.

After completing its movement to the right the carriage returns to its initial starting position beneath the magazines. During this return movement of the carriage various operations are effected by it including the release of the holding means 167 and shears 85 and their restoration to their normal open positions of rest, as previously explained. Another operation is effected by the returning carriage and that is to release the wound bobbins from the compartments 79 in order that they may fall out of these compartments into a receptacle, or be otherwise taken care of, as will later be explained. The wound bobbins in the compartments 79 are held therein by strips 80 which form the bottoms of the compartments. These strips are united in a frame which is arranged to slide laterally beneath the container 77 and its compartments 79. The strips 80 are mounted in the frame at approximately equal distances 81 apart. In consequence as the louvre-like frame is moved backward and forward beneath the container the strips 80 will either close all the compartments 79 or, by lateral displacement of the frame, the spaces 81 between the strips will be aligned below the openings in the compartments 79 so that the bobbins are able to fall out. The strips 80 are held in position to normally close the bottom of the compartments 79, and hold therein the wound bobbins after they have been released to fall from the spindles, by means of a tension spring 164 interposed between the end of the framed strips and the frame of the machine. The strips are opened, so that the wound bobbins in the compartments 79 may fall out, by means of the carriage 68 and is effected through various elements which include a rod 82 secured to the end of the framed strips 80 with extension along

the bed 1 of the machine. This rod is made in two sections connected by a flexible joint 82'. The rod is provided with a head 83 having a bevelled fore edge 83', a back edge 83'', and a slot 83''' on its under side. The head bearing end of the rod is urged to have an upward displacement by means of a spring 82'' on the bed of the machine engaging the under side of the rod. Associated with the head 83 is a pawl 161 eccentrically pivoted by a pin 163 to the frame 1 of the machine so that the pawl will occupy by gravity a normally engaging position. The pawl is provided with an upright finger 162 by which it may be turned into a disengaging position. Arranged forward of the head 83 on the frame 1 of the machine is a pin abutment 160. The normal position of the head and pawl are as shown in Fig. 5 where the strips 80, subjected to the tension of the spring 164, are shown closing the compartments 79.

As the lever 66 approaches the end of its return movement, after supplying the spindles with fresh unwound bobbins, it engages the back edge 83'' of the head 83 thereby moving the head into engagement with the pin abutment 160. As the head of the rod 82 becomes thus moved the strips 80, normally closing the compartment 79, will be shifted into an open position as shown in Fig. 3. Engagement of the head with the pin abutment 160 tends to depress the head whereupon the lever 66 will pass up over the back edge 83'' of the head and ride over the head then coming to a position of rest, substantially as shown in Fig. 3. At this same time the strips 80 will continue to be held open, inasmuch as the pawl 161 will have engaged the slot 83''' in the under side of the head, whereby the head becomes locked between the pawl and the abutment 160, preventing its retraction by the spring 164. When the lever 66 is again activated by the clutch mechanism its initial movement is one in the direction of the arm 162 of the pawl, engaging this arm, and rocking the pawl as in Fig. 4, to disengage it from the head 83, thereby releasing the head, whereupon the strips 80 will be drawn to a closed position by the spring 164 closing the compartments 79. The lever 66 will then take a long sweep to the left during which time the strips 80 will be occupying their closed positions, and the head 83 and associated pawl 161 their normal positions of rest, as shown in Fig. 5.

A modification of the intercepting container for orderly discharge of the wound bobbins can be carried out on the lines illustrated in Figs. 7, 8 and 9. In Fig. 7, in contradistinction to the horizontal disposal of the bottom 80 in conjunction with sloped guide faces 84 (Fig. 1), the sloped guide faces 89 and the closure slides 90 are disposed on one inclined plane. In this way an improvement in face of the arrangement previously described consists in the fact that the falling bobbin moves in reliable fashion with its lower end into the immediate vicinity of the machine gear independently of the length of the bobbin, so that it is always ensured that the thread drawn upon during the fall of the bobbin will always move to within reach of the shears 85, even in the case of dissimilarity in the length of the bobbins. The slide 90 of each single compartment is controlled in a frame, exactly in the manner as previously described.

A further embodiment is illustrated in Fig. 8, in which the bobbins fall into intercepting troughs 91, the throughgoing bottoms 92 of which are inclined in relation to the spindle axis in the

position of interception. These intercepting troughs are open at the ends directed towards the bed 1 of the machine, whilst at the opposite ends they are pivotally mounted at 93 on the frame 6. In the position of interception, which is indicated in Fig. 8 in dash-dotted lines, the intercepting trough 91 is held by a roll 94, which is mounted vertically to a lever 96 pivotally mounted at 95. The fulcrum 95 is constituted by a shaft on a supporting arm 97 mounted on the frame 6. The roll 94, which would be capable of oscillatory motion by way of the pivoted lever 96, is held in position by a two-armed lever 98, which is pivotally mounted on the bearing 99, and the free arm of which is pivoted to a tie rod 100, so that any pressure or tension exerted on this tie rod causes a rocking movement on the part of the two-armed lever 98, so that the intercepting trough 91 is capable of rocking upwards and downwards under its own weight about the pivot 93. The wound bobbin 10 falling off the spindle 4 is caught in the intercepting trough 91 and owing to the slope slides therein towards the open end. Opposite to the open end of the trough 91 there is mounted on the frame 6 an arcuate stop plate 101 forming part of a circle having its centre coincident with the pivot 93. This stop plate 101 holds the bobbin 10 in the intercepting trough 91, so that the bobbin is properly retained in the position indicated in dash-dotted lines during the severing of the thread.

If a control movement of the connecting rod 100 derived from the cam drive rocks the trough 91 out of its intercepting position after completion of the cutting operation, the bobbin 10, owing to the arcuate form of the stop plate 101, is held in the trough during the rocking of the same until in an ejection position shown in Fig. 8 a suitable aperture 102 in the plate 101 enables the bobbin 10 to slide out of the trough 91. In place of the aperture 102 the stop plate 101 can also be so dimensioned that it terminates in front of the position in which the bobbin slides out. The bobbin 10 leaving the trough 91 now slides with its lower end in front into a conveying box 103, which is conveniently located on a sloped surface 104, so that the bobbins successively leaving the troughs are caused to assume an upright position side by side in the box 103. In this connection the arrangement may also be such that, as in the modified arrangement illustrated in Fig. 9, an even advance of the conveying box 103 on the sloped surface 104 is brought about during the successive discharge of the bobbins, so that an orderly disposal of the bobbins 10 one behind the other is obtained.

In spinning and weaving mills a usual mode of conveying weft and other bobbins makes use of a studded board, on which the wound bobbins having central passages are placed over studs or pins usually mounted on the board in four rows. Heretofore it has been necessary to place the bobbins on these boards by hand. As compared with boxes, in which the bobbins are situated loosely in superimposed or adjacent disposal, the boards have the advantage that they are more handy and they also enable the operator attending the loom to obtain immediately full knowledge with regard to a particular shade of colour, the quantity of yarn on hand and the nature of the yarn.

The combination of these advantages with those of the orderly discharge of the wound bobbins from a winding machine in accordance with

the invention is shown in the modification according to Fig. 9 and in the detailed views in Figs. 10 to 14.

As in Fig. 8, there is used also in this modification a pivotally mounted trough 91 suspended in similar fashion as at 93 and having the same form of rocking control, which latter, for the purpose of facilitating comprehension, has consequently been omitted from Fig. 9. There is likewise provided an arcuate stop plate 101, this arc being part of a circle having its centre at 93. At its bottom it possesses in place of the simple aperture 102 in the embodiment according to Fig. 8 a sleeve 105, so that the wound bobbin 10 leaving the intercepting trough 91 is guided in its movement until being taken over by the board 106 and the studs or pins 107 mounted thereon.

Further, the intercepting troughs are not, as in the arrangement according to Fig. 8, disposed in accordance with the spacing of the spindles. At the bottom the single troughs, as shown in Fig. 10, are no longer separated by V-shaped partitions, but are so formed with the side-walls 108 in conjunction with the bottom that the bobbins falling into the same come to rest in a spacial disposal corresponding to the four rows on the studded board. Accordingly also in the example of the four-spindle machine four guide sleeves 105 are provided in conjunction with a thoroughgoing stop plate 101. The studded board 106 is fitted to slide loosely in the inclined frame 109, as shown in Figs. 9, 11, 12, 13, 14. Each board possesses at its end a stop plate 110 projecting at the bottom.

If the studded board is fitted in the frame 109, it slides, owing to the sloped position, into the frame 109 until the stop plate 110 moves into engagement with a toothed shaft 111. The toothed shaft 111 is mounted to rotate below the frame 109 in bearings 112, 113, and comprises a cylindrical roller portion, on which there are arranged in spiral distribution teeth 114 spaced axially to correspond to the distance between two rows of studs on the board 106. The distance spirally from one tooth 114 to the next is, as stated, equal to the spacing between two rows of studs and at an angle of rotation which is dependent on the extent of rotation of the control means for the shaft 111. The shaft 111 is coupled to the trough, for example by means of a ratchet gear 115. On the trough 91 there is rigidly mounted a lever 116, which participates in the rocking motion of the trough out of the intercepting position into the position of ejection. At the end of the lever 116 there is provided a connecting rod 117 which, as shown in Fig. 14, reciprocates a pivotally mounted lever 118, which is made integral with the ratchet gear 115.

If the connecting rod 117 upon the upward movement of the trough 91 has a pull exerted thereon by the lever 116, an angular movement will be imparted to the shaft 111 by way of the ratchet gear 115. The first tooth 114 (Figs. 11, 12, 14) moves out of engagement with the stop plate 110, and owing to the slope of the frame 109 the studded board slips forward until it is stopped by the next tooth after completion of the angular movement. Upon the subsequent rocking movement of the trough 91 into the position of discharge and under the pressure transmitted by the rod 117 the ratchet 115 runs idly on the ratchet head of the shaft 111.

The emerging bobbin can accordingly be

picked up in secured position of the studded board, and it is only the new upward rocking movement of the intercepting trough into the new position of readiness that causes in the meantime an advance of the board. The studded board 106 accordingly has the bobbins applied successively thereto, and at the end it slides into a removal frame 119, from which it can readily be taken and conveyed to a desired point.

In order after one studded board has been filled to have a second board in readiness there is provided on the frame 109 a second frame 120, which in accordance with Figs. 11 and 13 attends to the advance of a replacement board. The replacement board 106a is held in the position of readiness by a locking lever 121 against its stop plate 110a, which lever is rotatably mounted on the frame 109 about a stud 122. At the free end of the double-armed lever 121 there is a running-on roll 123, which acted upon by the spring 124 controls the position of the board 106 to which the bobbins are being applied. If upon progressive downward movement of the first board 106 after the last row of bobbins has been applied the roller 123 is able to rock freely under the action of the spring 124, the lever 121 releases the stop 110a of the second board 106a. The board 106a comes under control of the pressure lever 125, which is acted upon by the spring 126, into the position of readiness of the main frame 109, and with the stop plate 110 is now stopped by the first tooth 114 on the shaft 111 with the first row below the ejection tubes 105.

The thread or yarn 128 drawn freely in the known manner from the spool 127 is conducted by a guide 129 to a reversing wheel 130 (Figs. 1 and 2), which if necessary can be furnished as desired with thread-braking means of the conventional kind. From this reversing wheel 130 the thread 128 passes to a tensioning eye 131 mounted on a rod 132. This rod 132 is secured to a comb 133, which is pivotally mounted on a shaft 134 eccentrically to its centre of gravity. The shaft 134 in turn is secured at both ends by means of rocking levers 134a to a shaft 135, which is rotatably mounted in bearings 136 secured to the gear box 3. The bearings 136 form at the same time the bearings for a shaft 137, on which there are mounted cam levers 138. The shaft 137 receives by means of the connecting rod 139 an oscillatory motion from the eccentric drive 140, so that the cam levers 138 have a continuous oscillatory motion imparted to them. The rods 132 carrying the tension eyes 131 are held in their outermost position by a yoke 141, which is secured to the frame and extends over all spindles, and this position is maintained by the pull of the thread 128 being wound. If a break in the thread occurs, the comb 133, owing to the eccentric nature thereof, and the rod 132, by reason of the eccentric location of the centre of gravity, have the tendency to approach the appertaining cam lever 138. During this powerful reciprocation of the cam lever 138 the comb 133 moves into engagement with the cam lever and receives a blow, which is transmitted to the shaft 134 and by way of the rocking levers 134a imparts a rocking motion to the shaft 135. This rocking motion can be availed of in desired fashion for disengaging the spindle drive.

It will first be assumed that the spindles are being driven and winding of the bobbins taking place. The thread guide rods 5 are being reciprocated and turned and the thread guide carriers 25 are being moved progressively outwardly by

and upon these rods as they are turned. The arm 49 of the control lever will then be latched to the fork 41, and the line of levers connecting therewith, including the arm 49' of the control lever and the lever 51, will be occupying positions where the shaft 53 will be turned to position where it, through the linkage 47, will be holding the thread guide carriers 25 in threaded engagement with the thread guide rods on which they are mounted; the stop actuating shaft 62 for the spindle and thread guide drive will then be occupying an engaging position to permit of the operation of these drives for the spindles and thread guides; the lever 51 will then be occupying a disengaged position with relation to the cam gear 56 of the clutch mechanism; the control for the bobbin presser mechanism will then be in an inactive position allowing the bobbin pressers to be in engagement with the bobbins being wound for holding them in place, the carriage 68 will then be in a position of rest beneath the magazines 144 in readiness to receive a fresh supply of unwound bobbins, and the strips 80 will then be occupying an open position with relation to the bottoms of the compartments 79 into which the wound bobbins are adapted to fall when released.

When now the wind has been completed on the bobbins one of the thread guide carriers 25 will engage the stop 35. Thereupon the fork 41 will be tripped releasing the control lever, through release of its latched arm 49, and the position of this lever and the lever 51 will become changed under the tensional control of the spring 54. The first immediate action is to release the thread guide carriers from their threaded engagement with the thread guide rods effected by the reverse turning of the shaft 53 and intermediate connections. On the release of the thread guide carriers 25 from the thread guide rods the carriers will be returned to their initial positions by action of the compressed springs 34, when, on account of the continued rotation of the spindles before actual stoppage, the connecting threads will become disposed to connect with each bobbin at a point adjacent its head. The drives for the bobbins and thread guides will be stopped through reverse turning of the shaft 62. The lever 51 will activate the clutch mechanism whereupon on rotation of the cam gear 56 and cam 71 the mechanism controlling the bobbin pressers will release the wound bobbins. At this same time the carriage 68 will be moved to complete its movement to the right as shown in Fig. 2, thereby tripping the pawl 161 and permitting the strips 80 to close the bottoms of the compartments 79 into which the wound bobbins are about to fall. This closure of the bottoms of the compartments 79 takes place before the wound bobbins are released through release of the mechanism which releases the bobbin pressers, the action of release being sufficiently retarded to permit of the closure of the compartments. By this same movement of the carriage to the right the gripper blades 149 will be moved into the magazines, and a single bottom lay of unwound bobbins released onto the carriage. Thereupon the carriage will be moved with a long sweep to the left into a position beneath the spindles whereupon the magazines will again become closed and the grippers 149 released from the magazines. On its way to the position beneath the spindles the carriage will, through the blade 158 carried by it, position the trailing thread connecting with the wound bobbins, al-

ready deposited in the compartment 79, into positions where the threads will extend over the mandreled heads of the bobbins and into positions where the threads will be held by elements 167 and cut by elements 85 actuated by the carriage, the holding of the thread ends continuing after the cutting inasmuch as the cutting takes place below where the threads are being held. As the movement of the carriage continues the bobbins carried by it will be lifted and positioned between the mandreled heads of the spindles and the bobbin pressers then occupying a disengaging position. Thereupon, through the action of its actuating cam 71 the mechanism controlling the bobbin pressers will release them to hold the bobbins in place, the trailing threads then being bound between the ends of the bobbins and the mandreled heads of the spindles so that the threads will wind upon the bobbins when the wind is continued. As soon as the carriage has supplied the spindles with a fresh supply of bobbins it returns to its position of rest beneath the magazines. As it returns it allows the means which holds the trailing threads and shears to resume their normal disengaging positions. The return of the carriage also opens the bottoms 80 to the compartments 79 allowing the wound bobbins to fall out and be disposed of as may be desired. This opening of the bottoms of the compartments is occasioned by the carriage striking the head 83, moving this head into a position where it becomes bound between the pawl 161 and the abutment 160. This marks the completion of the return movement of the carriage, the clutch mechanism then having completed its cycle of rotation, whereupon the cam 56a on the under side of the cam disk 56 will have depressed the lever 51 thereby throwing the control lever again into latched engagement with the fork 41, and this changed position of the levers again throws the thread guide carriers 25 into threaded engagement with the thread guide rods, and again starts the drive for the spindles and thread guide rods, when the operation is repeated, the cam plate 56 of the clutch mechanism in the meantime being locked in its disengaged position.

The winding machine having now been fully described, it may be pointed out that the invention is in no way limited to the exact embodiment of the single parts as illustrated and described. Various other means may be employed within the meaning of the invention without departing from the scope of the annexed claims.

What I claim as new and desire to secure by Letters Patent is:

1. In a bobbin winding machine having a winding spindle, the combination comprising a rotatable threaded traverse bar, a thread guide carrier including a member adapted and arranged to have either an engaging relation with the threads on said bar for obtaining progressive movement of said carrier thereon as the bar is rotated or occupy a disengaging relation to the threads on said bar, shiftable mechanism controlling said member whereby it may be made to occupy its engaging or disengaging relation as aforesaid, and single variable means for operating said shiftable mechanism whereby in the operation of the machine it will actuate said member to occupy an engaging or disengaging relation to said bar, engagement at the beginning of the wind on a bobbin and disengagement at the termination of the wind preliminary to release of the bobbin from the winding spindle.
2. In a bobbin winding machine having a wind-

ing spindle, the combination comprising a rotatable threaded traverse bar, a thread guide carrier including a member adapted and arranged to have either an engaging relation with the threads on said bar for obtaining progressive movement of said carrier thereon from an initial position as the bar is rotated or occupy a disengaging relation to the threads on said bar, shiftable mechanism controlling said member whereby it may be made to occupy its engaging or disengaging relation as aforesaid, means for operating said shiftable mechanism whereby in the operation of the machine it will actuate said member to occupy an engaging or disengaging relation to said bar, engagement at the beginning of the wind on a bobbin and disengagement at the termination of the wind preliminary to release of the bobbin from the winding spindle, and a spring arranged upon said traverse bar tensioned by progressive movement of the carrier during the formation of the wind and acting to return said thread guide carrier back to its initial position when said member is occupying at the termination of the wind its disengaging relation to the threads on said bar.

3. In a bobbin winding machine the combination comprising a rotatable threaded traverse bar, a thread guide carrier including a member adapted and arranged to have either an engaging relation with the threads on said bar for obtaining progressive movement of said carrier thereon as the bar is rotated, or occupy a disengaging relation to the threads on said bar, shiftable mechanism controlling said member whereby it may be made to occupy its engaging or disengaging relation as aforesaid, means for operating said shiftable mechanism whereby in the operation of the machine it will actuate said member to occupy an engaging or disengaging relation to said bar including a pivoted lever by the reverse turning of which said mechanism is activated to engage or disengage said member from said bar, a displaceable latch with which said lever has engagement, tension means controlling said latch whereby it will retain said lever in a determinate turned position when said member is in engagement with said threaded bar, tension means normally operating to exert stress on said lever and turn said lever when released from said latch whereby it will actuate said shiftable mechanism to disengage said member from said bar, and means for opening said latch for releasing said lever whereby it may be turned as aforesaid.

4. In a bobbin winding machine the combination comprising a rotatable threaded traverse bar, a thread guide carrier including a member adapted and arranged to have either an engaging relation with the threads on said bar for obtaining progressive movement of said carrier thereon as the bar is rotated or occupy a disengaging relation to the threads on said bar, shiftable mechanism controlling said member whereby it may be made to occupy its engaging or disengaging relation as aforesaid, means for operating said shiftable mechanism whereby in the operation of the machine it will actuate said member to occupy an engaging or disengaging relation to said bar including a pivoted lever by the reverse turning of which said mechanism is activated to engage or disengage said member from said bar, a displaceable latch with which said lever has engagement, tension means controlling said latch whereby it will retain said lever in a

determinate turned position when said member is in engagement with said threaded bar, means connected to said lever and by which said lever is reversely turned including a tension device distorted when said lever is latched and exerting stress to turn said lever when released from said latch whereby it may then operate to actuate said shiftable mechanism to disengage said member from said bar, and mechanism in co-operative engagement with said last named means whereby it will be operated at timed intervals and in successive stages of operation to turn said lever into its latched position and permit of its turning when released from said latch, and means for opening said latch for releasing said lever.

5. In a bobbin winding machine the combination comprising a rotatable threaded traverse bar, a thread guide carrier including a member adapted and arranged to have either an engaging relation with the threads on said bar for obtaining progressive movement of said carrier thereon from an initial position as the bar is rotated or occupy a disengaging relation to the threads on said bar, shiftable means controlling said member whereby it may be made to occupy its engaging or disengaging relation as aforesaid, a latchable tensioned mechanism operating to control said shiftable means whereby in the operation of the machine it will actuate said member to occupy an engaging or disengaging relation to said bar and to maintain said engagement of the member when said mechanism is latched and to effect disengagement thereof when said mechanism is unlatched, and means whereby said latchable mechanism will be unlatched by the operation of said thread guide carrier at the termination of its progressive movement.

6. In a bobbin winding machine having a bobbin drive including a spindle head and an axially shiftable bobbin presser adapted to hold a bobbin between it and said head, a thread guide carrier movable for obtaining a lay of thread on said bobbin, means for shifting the position of said bobbin presser for releasing the held bobbin, including latchable tensioned elements normally inactive when latched and mechanism activated by said latchable elements when unlatched, constructed and arranged to throw said bobbin presser into a bobbin releasing position, a latch for retaining said latchable elements tensioned as aforesaid, tension means controlling said latch whereby it will retain said latchable elements, and means whereby said carrier at the termination of the winding movement will undo said latch releasing said latchable elements whereby the parts activated thereby when said latchable elements are released will shift said bobbin presser into a bobbin releasing position.

7. In a bobbin winding machine having a bobbin drive including a spindle head and an axially shiftable bobbin presser adapted to hold a bobbin between it and said head, the combination comprising a tension device normally active to hold said bobbin presser in a bobbin engaging position and allow of its retraction into a disengaging position with relation to the bobbin for releasing it, mechanism operating when activated to retract the bobbin presser into a disengaging position and allow of its return into an engaging position at timed intervals and in successive stages, means for activating said mechanism at timed intervals and in successive stages including tensioned latchable elements adapted and arranged to activate said mecha-

nism when unlatched, means for latching said elements tensioned as aforesaid, and means for undoing said latch whereby said elements will be released to activate said mechanism and thereby move said bobbin presser into a disengaging position as aforesaid.

8. In a bobbin winding machine having a bobbin drive including a spindle head and an axially shiftable bobbin presser adapted to hold a bobbin between it and said head, a tension device normally active to hold said bobbin presser in a bobbin engaging position and allow of its retraction into a disengaging position with relation to the bobbin for releasing it, mechanism operating when activated to retract the bobbin presser into a disengaging position and allow of its return into an engaging position at timed intervals and in successive stages, means for activating said mechanism at timed intervals and in successive stages including tensioned latching elements adapted and arranged to activate said mechanisms when unlatched, means for latching said elements tensioned as aforesaid, a thread guide carrier movable for obtaining a lay of thread on said bobbin, means whereby said carrier will undo said latch for releasing said latching elements at the termination of the winding movement, and means whereby said activated mechanism will during the operation thereof effect a relatching of said latching elements after said bobbin presser has been allowed to resume its engaging position.

9. In a bobbin winding machine the combination with mechanism for winding a bobbin and effecting its release when wound including relatively movable holding means adapted to hold the bobbin between them, of mechanism for automatically recharging said holding means with an unwound bobbin including a magazine disposed laterally of said holding means having a channel holding a plurality of unwound bobbins, a closure slide at the bottom of said magazine retained to close said channel and shiftable to open said channel, said slide having a gripper capable of being introduced into said channel separating the bottom bobbin from those above it on the shifting of said slide into its open position, a reciprocable carriage for receiving the bobbin dropped from said magazine on the opening of said slide, means for opening said slide, and means for reciprocating said carriage.

10. In a bobbin winding machine the combination with mechanism for winding a bobbin and effecting its release when wound including relatively movable holding means adapted to hold the bobbin between them, of mechanism for automatically recharging said holding means with an unwound bobbin including a magazine disposed laterally of said holding means having a channel for holding a plurality of unwound bobbins, a closure slide at the bottom of said magazine retained to close said channel and shiftable to open said channel, means for holding said slide normally closed and permitting of the opening thereof, said slide having a gripper capable of being introduced into said channel separating the bottom bobbin from those above it on the shifting of said slide into its open position, a reciprocable carriage for receiving the bobbin dropped from said magazine on the opening of said slide, means borne by said carriage for opening said slide during the reciprocation of the carriage, and means for reciprocating said carriage.

11. In a bobbin winding machine having mech-

anism for winding a bobbin and effecting its release when wound, the combination comprising relatively movable holding means for the bobbin including a spindle head and an axially shiftable bobbin presser adapted to hold a bobbin between it and said head, a tension device normally active to hold said bobbin presser in bobbin engaging position and allow its retraction into a disengaging position with relation to the bobbin for releasing it, mechanism for automatically recharging said holding means with an unwound bobbin after the releasing of a wound bobbin therefrom including a magazine disposed laterally of said holding means having a channel for holding a plurality of unwound bobbins, means whereby the bottom bobbin in said magazine may be released to drop from said magazine, a reciprocable carriage for receiving the bobbin dropped from said magazine, said carriage comprising the body of the carriage and a relatively movable tray having an opening for receiving the bobbin dropped from said magazine as aforesaid, means for combining said body and tray whereby said tray may be elevated with relation to said body, a way along which said carriage is movable during reciprocation thereof to occupy a position beneath said holding means, means whereby said bobbin carrying tray when positioned beneath said holding means during the reciprocation of said carriage may be elevated and an unwound bobbin carried thereby be positioned between said holding means to be retained thereby, a normally latent operating mechanism, means whereby said operating mechanism when activated will retract said bobbin presser into a disengaging position before the unwound bobbin is elevated from out of said bobbin carrying tray and positioned between said presser and said head as aforesaid, and afterwards release the bobbin presser into its said engaging position for holding the positioned bobbin before dropping of said tray, means whereby said mechanism when activated will reciprocate said carriage in proper timed relation to the control of said bobbin presser as aforesaid, and means for activating said operating mechanism at timed intervals and successive stages of operation.

12. In a bobbin winding machine having mechanism for winding a bobbin and effecting its release when wound the combination comprising relatively movable holding means for the bobbin including a spindle head and an axially shiftable bobbin presser adapted to hold a bobbin between it and said head, a tension device normally active to hold said bobbin presser in bobbin engaging position and allow its retraction into a disengaging position with relation to the bobbin for releasing it, mechanism for automatically recharging said holding means with an unwound bobbin after the release of a wound bobbin therefrom including a magazine disposed laterally of said holding means having a channel for holding a plurality of unwound bobbins, means whereby the bottom bobbin in said magazine may be released to drop from said magazine, a reciprocable carriage for receiving the bobbin dropped from said magazine, said carriage comprising the body of the carriage and a relatively movable tray having an opening for receiving the bobbin dropped from said magazine as aforesaid, means for combining said body and tray whereby said tray may be elevated with relation to said body, a way along which said

carriage is movable during reciprocation thereof to occupy a position beneath said holding means, means whereby said bobbin carrying tray when positioned beneath said holding means during the reciprocation of said carriage may be elevated and an unwound bobbin carried thereby be positioned between said holding means to be retained thereby, a normally latent operating mechanism, means whereby said operating mechanism when activated will retract said bobbin presser into a disengaging position before the unwound bobbin is elevated from out of said bobbin carrying tray and positioned between said presser and said head as aforesaid, and afterwards release the bobbin presser into its said engaging position for holding the positioned bobbin before dropping of said tray, means whereby said mechanism when activated will reciprocate said carriage in proper timed relation to the control of said bobbin presser as aforesaid, means for activating said operating mechanism at timed intervals and successive stages of operation including tensioned latchable elements adapted and arranged to activate said operating mechanism when unlatched, means for latching said elements tensioned as aforesaid, and means for undoing said latch whereby said elements will be released to activate said operating mechanism and thereby effect the operation of said bobbin presser and said carriage as aforesaid.

13. In a bobbin winding machine having mechanism for winding a bobbin and effecting its release when wound, the combination comprising relatively movable holding means for the bobbin including a spindle head and an axially shiftable bobbin presser adapted to hold a bobbin between it and said head, a tension device normally active to hold said bobbin presser in bobbin engaging position and allow its retraction into a disengaging position with relation to the bobbin for releasing it, mechanism for automatically recharging said holding means with an unwound bobbin after the releasing of a wound bobbin therefrom including a magazine disposed laterally of said holding means having a channel for holding a plurality of unwound bobbins, means whereby the bottom bobbin in said magazine may be released to drop from said magazine, a reciprocable carriage for receiving the bobbin dropped from said magazine, said carriage comprising the body of the carriage and a relatively movable tray having an opening for receiving the bobbin dropped from said magazine as aforesaid, means for combining said body and tray whereby said tray may be elevated with relation to said body, a way along which said carriage is movable during reciprocation thereof to occupy a position beneath said holding means, means whereby said bobbin carrying tray when positioned beneath said holding means during the reciprocation of said carriage may be elevated and an unwound bobbin carried thereby be positioned between said holding means to be retained thereby, a normally latent operating mechanism, means whereby said operating mechanism when activated will retract said bobbin presser into a disengaging position before the unwound bobbin is elevated from out of said bobbin carrying tray and positioned between said presser and said head as aforesaid, and afterwards release the bobbin presser into its said engaging position for holding the positioned bobbin before dropping of said tray, means whereby said mechanism when activated will reciprocate said carriage in proper timed relation to the control of

said bobbin presser as aforesaid, means for activating said operating mechanism at timed intervals and successive stages of operation including tensioned latchable elements adapted and arranged to activate said operating mechanism when unlatched, means for latching said elements tensioned as aforesaid, a thread guide carrier movable for obtaining a lay of thread on said bobbin, means whereby said carrier will undo said latch for releasing said latchable elements at the termination of the winding movement, and means whereby said activating mechanism will during the operation thereof effect a relatching of said latchable elements after said bobbin presser has been allowed to resume its engaging position and said carriage has been returned to its initial position.

14. In a bobbin winding machine having mechanism for the release of a wound bobbin and its replacement by an unwound bobbin, the combination comprising mechanism for holding the bobbin during the winding thereof and for effecting its release when wound including a spindle head and an axially shiftable bobbin presser adapted to hold the bobbin between it and said head, a thread guide, means for returning said thread guide to the base end of the wound bobbin adjacent said spindle head, a container for receiving the released bobbin with trailing thread leading thereto and extending by said spindle head, holding means located between the wound bobbin in said container and said spindle head for holding the trailing thread in position where it will lie held between said head and the end of an unwound bobbin applied to said head when the unwound bobbin is clamped between said head and said axially shiftable bobbin presser whereby the thread will engage the unwound bobbin to become wound thereon on continuance of the wind.

15. In a bobbin winding machine having mechanism for the release of a wound bobbin and its replacement by an unwound bobbin, the combination comprising mechanism for holding the bobbin during the winding thereof and for effecting its release when wound including a spindle head and an axially shiftable bobbin presser adapted to hold the bobbin between it and said head, a thread guide, means for returning said thread guide to the base end of the wound bobbin adjacent said spindle head at the termination of the wind, a container for receiving the released bobbin whereby the trailing thread leading thereto may be directed to extend by said head, holding means located between the wound bobbin in said container and said spindle head for holding the trailing thread in position where it will be held to lie between said head and the end of an unwound bobbin applied to said head when said unwound bobbin is clamped between said head and said axially shiftable bobbin presser whereby the thread will engage the unwound bobbin to become wound thereon on continuance of the wind and means for directing the trailing thread to said holding means.

16. In a bobbin winding machine having mechanism for the release of a wound bobbin and its replacement by an unwound bobbin the combination comprising mechanism for holding the bobbin during the winding thereof and for effecting its release when wound including a spindle head and an axially shiftable bobbin presser adapted to hold the bobbin between it and said head, a thread guide, means for returning said thread guide to the base end of the wound bob-

bin adjacent said spindle head at the termination of the wind, a container for receiving the released bobbin whereby the trailing thread leading to said released bobbin may be directed to extend by said head, holding means located between the wound bobbin in said container and said spindle head for holding the trailing thread whereby it may be severed and whereby after severance it may lie held between said spindle head and the head of an unwound bobbin applied to said head when said unwound bobbin is clamped between said head and said axially shiftable bobbin presser, and means for severing the thread when held as aforesaid at a point between said holding means and the wound bobbin in said container.

17. In a bobbin winding machine having mechanism for the release of a wound bobbin and its replacement by an unwound bobbin, the combination comprising mechanism for holding the bobbin during the winding thereof and for effecting its release when wound including a spindle head and an axially shiftable bobbin presser adapted to hold the bobbin between it and said head, a thread guide, means for returning said thread guide to the base end of the wound bobbin adjacent said spindle head at the termination of the wind, a container for receiving the released bobbin whereby the trailing thread leading to said released bobbin may be directed to extend by said head, holding means located between the wound bobbin in said container and said spindle head for holding the trailing thread whereby it may be severed and whereby, also, after severance it will be held to lie between said head and the head of an unwound bobbin applied to said head when said unwound bobbin is clamped between said head and said axially shiftable bobbin presser, means for directing the trailing thread to said holding means whereby it may be severed and held as aforesaid, and means for severing the trailing thread when held as aforesaid at a point between said holding means and the wound bobbin in said container.

18. In a bobbin winding machine the combination with mechanism for holding the bobbin during the winding thereof and for effecting its release when wound including a spindle head and an axially shiftable bobbin presser adapted to hold the bobbin between it and said head, of mechanism for recharging said spindle head and bobbin presser with an unwound bobbin after the release of a wound bobbin including a movable carriage, a thread guide, means for controlling said thread guide whereby it will be returned to the base portion of the wound bobbin adjacent said spindle head preliminary to the release of the bobbin after the winding thereof, a container for receiving a released bobbin after the winding thereof whereby the trailing thread leading to said released bobbin may be directed to extend by said head, means operable to hold the trailing thread in said directed position whereby the thread will lie held between said head and the end of an unwound bobbin applied to said head by said recharging mechanism and clamped between it and said axially shiftable bobbin presser whereupon the thread will engage the bobbin to become wound thereon on continuance of the wind, a cutter operable to cut the thread when held as aforesaid at a point between said thread holding means and the wound bobbin in said container, and means borne by said carriage whereby said trailing thread will be positioned to be held as aforesaid

and whereby, also, said thread holding means and said cutter will be operated in successive stages of operation during the movement of said carriage.

- 5 19. In a bobbin winding machine the combination with mechanism for holding the bobbin during the winding thereof and for effecting its release when wound including a spindle head and an axially shiftable bobbin presser adapted to hold the bobbin between it and said head when occupying an engaging position, of mechanism for recharging said spindle head and bobbin presser with an unwound bobbin after the release of a wound bobbin including a movable carriage, a thread guide, means for controlling said thread guide whereby it will be returned to the base portion of the wound bobbin adjacent said spindle head preliminary to the release of the bobbin after the winding thereof, mechanism controlling the action of the bobbin presser for releasing the wound bobbin, a container for receiving the wound bobbin after the release thereof whereby the trailing thread leading to said released bobbin may be directed into a position where it may be held and cut when extending by said spindle head, holding mechanism for said thread, a cutting mechanism for said thread located between said holding mechanism and the wound bobbin in said container from 10 which the trailing thread extends, means borne by said carriage for directing the trailing thread into position where it may be held and cut, means borne by said carriage for activating said holding mechanism and said cutting mechanism 15 in relative sequence, first the holding mechanism and then the cutting mechanism, whereby the thread holding mechanism will continue to hold the trailing thread after the cutting thereof with the trailing thread then extending by 20 said spindle head to lie clamped between said spindle head and the head of an unwound bobbin when said unwound bobbin, applied to said head from off said carriage, is clamped between said head and said axially shiftable bobbin presser when said presser is released to occupy its 25 engaging position.

20. In a bobbin winding machine the combination with mechanism for winding the bobbin, mechanism for holding the bobbin during the 30 winding thereof and for effecting its release when wound, mechanism for recharging said bobbin holding mechanism with an unwound bobbin after the release of a wound bobbin including a movable carriage, a container for receiving and holding 35 a released bobbin after the winding thereof, a displaceable bottom to said container whereby the wound bobbin may be released therefrom, and means whereby said displaceable bottom to said container may be opened and afterwards 40 released to close by said carriage at determinate periods during the operation thereof.

21. In a bobbin winding machine the combination with mechanism for winding the bobbin, mechanism for holding the bobbin during the 45 winding thereof and for effecting its release when wound, mechanism for recharging said bobbin holding mechanism with an unwound bobbin after the release of a wound bobbin including a movable carriage, a container for receiving and holding 50 a released bobbin after the winding thereof, a displaceable bottom to said container whereby the wound bobbin may be released therefrom, a spring for holding said bottom normally 55 closed, and means whereby said displaceable bottom 60 released to close by said carriage at determinate periods during the operation thereof.

- 70

- 75

tom may be opened and afterwards released to close by said carriage at determinate periods during the operation thereof including a rod having a head, and a pawl and an abutment in co-operative relation to said head of the rod substantially as described.

22. In a bobbin winding machine having a spindle drive, a bobbin releasing mechanism for releasing a wound bobbin from said drive, a thread guiding mechanism for obtaining a lay of thread on the bobbin, a stop actuating mechanism, a bobbin recharging mechanism, the combination therewith of means for controlling said various mechanisms at determinate intervals and in proper timed relation including a set of connected levers, one a control lever having a forward and reverse movement, a latch for maintaining said control lever and connected levers in a determinate turned position, means for tensionally maintaining the levers in said position whereby their position will change automatically when said control lever is released from said latch, means whereby said control lever may be released from said latch at the termination of the wind, a clutch mechanism activated by the released levers, and means whereby the released levers may automatically be reversely turned to their initial positions and said control lever re-latched as aforesaid.

23. In an automatic thread winding machine having a winding spindle from which a wound bobbin is discharged and replaced by an unwound bobbin and the trailing thread connecting with the discharged wound bobbin is bound between the winding spindle and a replaced unwound bobbin, the combination comprising means for intercepting the wound bobbin falling down from the spindle, said intercepting means comprising a container having an inclined face with which the falling wound bobbin has contact whereby it will be projected in a forward direction, a displaceable bottom to said container by which the fallen bobbins contained therein may be released therefrom, and means for opening the bottom of said container whereby the wound bobbin may be released therefrom.

24. In an automatic thread winding machine having a winding spindle from which a wound bobbin is discharged and replaced by an unwound bobbin and the trailing thread connecting with the discharged wound bobbin is bound between the winding spindle and a replaced unwound bobbin, the combination comprising means for intercepting the wound bobbin falling down from the spindle, the said intercepting means comprising a pivotally mounted trough, disposed at an angle to the plane of the spindles whereby a contained bobbin will be projected in a forward direction, a closure for the open end of said trough, and means for controlling said trough whereby it may be rocked in relation to said closure and a wound bobbin therein be released therefrom.

25. In an automatic thread winding machine having a winding spindle from which a wound bobbin is discharged and replaced by an unwound bobbin, means for intercepting the wound bobbin falling down from the spindle, said intercepting means comprising a pivotally mounted trough having a compartment corresponding in location with the location of a line of pins on a studded board arranged below said trough and which pins receive the wound bobbins released from said trough, a closure for the open end of

said trough, means for controlling said trough whereby it may be rocked in relation to said closure and wound bobbins therein released therefrom to fall upon the pins of said studded board, a studded board for receiving said released bobbins as aforesaid on the pins thereof, and mechanism in co-operative operation with said means for rocking said trough for an intermittent change of position of said studded board after one row of pins has received its full complement of bobbins.

26. In an automatic thread winding machine having a winding spindle from which a wound bobbin is discharged and replaced by an unwound bobbin, means for intercepting the wound bobbins falling down from said spindle, said intercepting means comprising a pivotally mounted trough having a bobbin receiving compartment corresponding in location with the location of a line of pins on a studded board arranged below said trough and which pins receive the wound bobbins released from said trough, a closure for the open end of said trough, means for controlling said trough whereby it may be rocked in relation to said closure and wound bobbins therein released therefrom to fall upon the pins of said studded board, ejection tubes borne by said closure through which the bobbins released from said trough are directed to pass to fall upon the pins of said studded board as aforesaid, a studded board for receiving said released bobbins as aforesaid on the pins thereof, and mechanism in co-operative operation with said means for rocking said trough for an intermittent change of position of said studded board after one row of pins has received its full complement of bobbins.

27. In an automatic thread winding machine having a winding spindle from which a wound bobbin is discharged and replaced by an unwound bobbin, means for intercepting the wound bobbins falling down from the spindle, said intercepting means comprising a pivotally mounted trough having a bobbin receiving compartment corresponding in location with the location of a line of pins on a studded board arranged below said trough and which pins receive the wound bobbins released from said trough, a closure for the open end of said trough, means for controlling said trough whereby it may be rocked in relation to said closure and wound bobbins therein released therefrom to fall upon the pins of said studded board, ejection tubes borne by said closure through which the bobbins released from said trough are directed to pass to fall upon the pins of said studded board as aforesaid, a studded board for receiving said released bobbins as aforesaid on the pins thereof, mechanism in co-operative operation with said means for rocking said trough for an intermittent change of position of said studded board after one row of pins has received its full complement of bobbins, and mechanism whereby another studded board may be positioned to take the place of said first studded board after said first studded board has received its full complement of bobbins.

28. In a bobbin winding machine having a winding mechanism for holding a bobbin adapted to receive the material to be wound, an element actuated to have both a reciprocal and a progressive movement for assisting in the lay of the material on said bobbin, a control mechanism including a control lever, a displaceable latch with which said lever has engagement, ten-

sion means controlling said latch whereby it will retain said lever when in latched engagement therewith, and an unlatching mechanism whereby said element at the end of its progressive movement will undo said latch at the termination of the wind for releasing said lever, said unlatching mechanism including a movable stop with which said element has engagement at the termination of the wind, and means whereby the latent position of said stop may be adjustably changed with relation to said element commensurate with the extent of wind on said bobbin.

29. In a bobbin winding machine having a winding mechanism for holding a bobbin adapted to receive the material to be wound, an element actuated to have both a reciprocative and a progressive movement for assisting in the lay of the material on said bobbin, a control mechanism including a control lever, a displaceable latch with which said lever has engagement, tension means controlling said latch whereby it will retain said lever when in latched engagement therewith, tension means controlling said lever distorted when said lever is latched and exerting force to turn said lever when unlatched, and an unlatching mechanism whereby said element at the end of its progressive movement will undo said latch at the termination of the wind for releasing said lever, said unlatching mechanism including a movable stop with which said element has engagement at the termination of the wind, and means whereby the latent position of said stop may be adjustably changed with relation to said element commensurate with the extent of wind on said bobbin.

30. In a bobbin winding machine having an

element movable to and fro in reverse directions, mechanism controlling said element to change the position thereof at determinate intervals including a latchable tensioned pivoted lever by the reverse turning of which said element is reversely turned, a displaceable latch with which said lever has engagement, tension means controlling said latch whereby it will retain said lever and element controlled by it in a determinate turned position, and means whereby on the release of said latch the unlatched lever tensioned as aforesaid and then released will operate to move said element into a reverse position.

31. In a bobbin winding machine having an element movable to and fro in reverse directions, mechanism for controlling said element to change the position thereof at determinate intervals including a set of connected levers, one a latchable control lever by which said element is reversely turned, a displaceable latch with which said control lever has engagement and by which it and said connected levers are maintained in a determinate turned position, means for tensionally maintaining the levers in said position whereby their position will change automatically when said control lever is released from said latch, releasable means controlling said latch whereby on the release thereof said control lever will be reversely turned for turning said element in a reverse direction and the position of said connecting levers changed, a clutch mechanism activated by the released levers, and means whereby the released levers may be automatically reversely turned to their initial positions and said control lever relatched as aforesaid.

HANS TRECKMANN.
